UNITED STATES PATENT OFFICE.

JOSEPH P. GOMES, OF NEW YORK, N. Y., ASSIGNOR OF ONE-HALF TO C. ABBOTT BUSH,
OF BROOKLYN, NEW YORK.

ARTIFICIAL TOOTH.

1,191,586.

Specification of Letters Patent.

Patented July 18, 1916.

Application filed February 8, 1916. Serial No. 76,943.

To all whom it may concern:

Be it known that I, JOSEPH P. GOMES, a citizen of the United States, and resident of the borough of Brooklyn, in the city and 5 State of New York, have invented a new and useful Improvement in Artificial Teeth, of which the following is a specification.

This invention relates to an improvement in artificial teeth, and more particularly to 10 the means of securing the facing of a tooth to the metal or other backing.

One of the objects is to provide a tooth having a structure formed in the back of the tooth or the surface which coacts with 15 the backing, which structure is equally well adapted for front teeth as well as bicuspids and molars.

A further object is to provide an interlocking engagement between the tooth and 20 the backing and to avoid weakening the body of the tooth by the undercut cavities for the backing member.

A practical embodiment of my invention is represented in the accompanying drawings, in which,

Figure 1 represents a vertical central section of a front tooth and backing showing my improved means for fastening them together. Fig. 2 represents a similar view 30 showing the tooth and backing separated. Fig. 3 represents a rear elevation of the tooth, Fig. 4 represents a rear and side elevation of the backing. Fig. 5 represents a plan view of a molar with the backing applied thereto. Fig. 6 represents a similar view with the backing removed. Fig. 7 represents an inverted plan view of the backing. Fig. 8 represents a vertical section of a molar and backing. Fig. 9 represents a 40 similar view with the backing removed. Fig. 10 represents a plan view of a bicuspid showing a modified form of fastening means. Fig. 11 represents an inverted plan view of the backing which coacts with the bicuspid, and Fig. 12 represents a vertical section of a 45 bicuspid and its backing.

In Figs. 1 to 4 inclusive, I have shown a backing having a front tooth or facing applied thereto, while Figs. 5 to 9 inclusive 50 show the same structure with a molar applied to a backing. Thus it will be seen that the body of both the front tooth facing and the molar being widely different, my improved structure is equally well adapted for

any tooth facing that may be applied to a 55 backing in crown, bridge or other work.

In Figs. 1 to 4 inclusive, the tooth or facing is denoted by 1, and is provided upon its rear surface 2 with one or more shallow cavities 3, which are undercut so as to form 60 a wall 4. The surface 2 is also provided with a ledge 5 extending across the tooth, which ledge is preferably undercut, as shown at 6, and has formed therein one or more sockets 7. A backing 8 of metal or 65 other suitable material is provided with one or more prongs 9, which are adapted to enter the sockets 7 in the undercut ledge 5. The backing 8 is provided with a beveled edge 10, which is adapted to fit the under- 70 cut ledge 5. The backing is also provided with one or more squared hooks 11, the free ends of which are adapted to enter the cavities and engage the wall 4 of the tooth. 75 These hooks 11 are preferably formed with sharp or squared edges so as to obtain a firmer grip in the cement 12, with which the cavities are filled when the backing is applied to the tooth. In practice, the cavities 80 and sockets 7 are scantily filled with cement 12 and the tooth or facing is placed in position with the prongs 9 entering the sockets 7. The hooks 11 are pressed into the cement 12 in the cavities 3, until the surface 2 bears against the backing 8, when the tooth 85 may be pushed upwardly causing the prongs 9 to seat in the sockets 7 and the free ends of the hooks 11 to engage the walls 4, thereby maintaining a firm bearing throughout the entire flat contacting face. Thus it will be 90 seen that the strength of the tooth is preserved by the shallow cavities and sockets being formed in the largest bulk of porcelain of the tooth, thus presenting a tooth which may be ground without making the tooth 95 thin and without the possibility of the tooth being split under the strain incident to the upward pressure.

In Figs. 5 to 9 inclusive, the tooth shown herein is a molar 13, and has its upper surface 14 inclined, which surface is provided with the shallow cavities 3, the ledge 5, and the sockets 7, as previously described with respect to Figs. 1 to 4 inclusive, which are adapted to coact with the backing 4, prongs 105 9, and hooks 11, as before described.

When the facing is quite narrow as in the bicuspid shown in Figs. 10 to 12 inclusive, I

find it sometimes advantageous to only use a single socket 15 which is adapted to coact with a hook 16 on the backing 17. It will be seen that by this structure the interlocking engagement between the backing and the facing does not weaken or make thin any portion of the body of the tooth and therefore does not sacrifice in any degree the strength of the facing. Furthermore, this 10 interlocking engagement between the backing and the tooth permits the use of a shorter bite than is now in common use.

It is evident that various changes may be resorted to in the form, construction and 15 arrangement of the several parts without departing from the spirit and scope of my invention, and hence I do not wish to limit myself to the specific details herein shown and described except as they may be particularly set forth in the claims.

What I claim is:

1. In an artificial tooth, a facing having an undercut ledge extending across the tooth and an undercut cavity, a backing provided 25 with an edge adapted to coact with said ledge and a hook arranged to engage said cavity for securing the facing to the backing.

2. In an artificial tooth, a facing having a 30 beveled undercut ledge extending across the tooth and an undercut cavity, a backing provided with a beveled edge adapted to coact with said ledge and a hook arranged to engage said cavity for securing the facing to the 35 backing.

3. In an artificial tooth, a facing having an undercut ledge extending across the tooth and undercut cavities, and a backing provided with an edge adapted to coact with 40 said ledge and a plurality of hooks arranged to engage said cavities for securing the facing to the backing.

4. In an artificial tooth, a facing having a

beveled undercut ledge extending across the tooth and undercut cavities, and a backing 45 provided with a beveled edge adapted to coact with said ledge and a plurality of hooks arranged to engage said cavities for securing the facing to the backing.

5. In an artificial tooth, a facing having 50 an undercut ledge extending across the tooth, sockets in said ledge and an undercut cavity and a backing provided with an edge adapted to coact with said ledge, prongs for said sockets and a hook arranged to engage 55 said cavity for securing the facing to the backing.

6. In an artificial tooth, a facing having a beveled undercut ledge extending across the tooth, sockets in said ledge and an 60 undercut cavity, and a backing provided with a beveled edge adapted to coact with said ledge, prongs for said sockets and a hook arranged to engage 65 said cavity for securing the facing to the backing.

7. In an artificial tooth, a facing having an undercut ledge extending across the tooth, sockets in said ledge and undercut cavities, and a backing provided with an edge 70 adapted to coact with said ledge, prongs for said sockets and a plurality of hooks arranged to engage said cavities for securing the facing to the backing.

8. In an artificial tooth, a facing having a beveled undercut ledge extending across the 75 tooth, sockets in said ledge and undercut cavities, and a backing provided with a beveled edge adapted to coact with said ledge, prongs for said sockets and a plurality of hooks arranged to engage 80 said cavities for securing the facing to the backing.

In testimony, that I claim the foregoing as my invention, I have signed my name, this seventh day of February, 1916.

JOSEPH P. GOMES.
